Patented July 8, 1924.

UNITED STATES PATENT OFFICE.

GEORGE G. SCARBOROUGH, OF GIRDLETREE, MARYLAND.

HEATING STOVE.

Application filed February 20, 1924. Serial No. 694,145.

To all whom it may concern:

Be it known that I, GEORGE G. SCARBOROUGH, a citizen of the United States, residing at Girdletree, in the county of Worcester and State of Maryland, have invented certain new and useful Improvements in Heating Stoves, of which the following is a specification.

This invention relates to heating stoves, and is an improvement over the construction shown in my prior Patent No. 1,343,645, dated June 15, 1920.

In the said prior patent, I have disclosed and claimed a heating stove consisting of an outer shell, an inner shell spaced therefrom and forming a passage for the products of combustion, and a central fuel feeding magazine arranged within the shell.

An object of the present invention is to provide an improved construction of inner shell and fuel feeding magazine which will prevent the fuel from burning above the lower end of the magazine.

A further object is the provision of an inner shell having an inclined bottom extending to the bottom of the fuel feeding magazine and forming a restricted passage for the passage of the products of combustion.

In the accompanying drawings, I have shown one embodiment of the invention.

In this showing:

Figure 1 is a central vertical sectional view.

Figure 2 is a perspective view of the fuel feeding magazine.

Figure 3 is a similar view of the inner shell, and,

Figure 4 is a horizontal sectional view on line 4-4 of Figure 1.

Referring to the drawings, the reference numeral 1 designates a cylindrical body portion having a grate 2 arranged therein. The grate divides the body portion of the stove into a fire box 3 and an ash pit 4. The body portion of the stove may be supported on suitable legs 5. The ash pit is provided with a door 6, for the removal of ashes and for regulation of the draft. The upper end of the body portion is provided with an annular heat absorbing and radiating element 7, having a substantially thick cross sectional area. This element is provided with an upstanding flange 8. An outer shell 9 rests upon this flange, forming a gas tight joint between the shell and the body portion. An inner shell 10 is arranged within the outer shell slightly spaced therefrom,

forming an annular passage 11 for the escape of gases and products of combustion. The upper end of the inner shell is open and is adapted to be partially closed by a cover 12. The inner shell is further provided with legs 13, projecting downwardly and adapted to rest on the flange 8. These legs are of a width substantially equal to the width of the annular space 11 and serve as spacing bars to retain the inner shell and outer shell in the desired position with respect to each other. Beyond the point where the legs project from the inner shell, the inner shell is provided with an inclined bottom 14.

A fuel feeding magazine 15 is arranged centrally of the inner shell. As shown, the inclined bottom is provided with a central opening adapted to receive the lower end of the fuel feeding magazine. The flange 16 is arranged on the exterior of the magazine adjacent the bottom and is adapted to rest upon the inclined bottom of the inner shell to support the lower end of the magazine. The upper end of the magazine extends through an opening in the lid 12, the opening being of slightly larger diameter than the magazine, as shown. A sealing ring 17 is arranged on the lid and is adapted to snugly receive the upper end of the magazine. The space between the inner shell and the fuel feeding magazine forms a dead-air chamber 18. This space is of a substantial cross sectional area and serves as an effective heat insulating means between the magazine and the passage 11. The stove is provided with a top 19. The outer edge of the top is provided with a depending flange 20 and an outwardly extending flange 21. The depending flange fits within the outer casing and the flange 21 rests on the top of the outer casing. The outer casing is provided with ears 20' and bolts 21' are passed through the flange 21 and these ears. Nut 22' may be arranged on these bolts. The inner end of the top snugly receives the upper end of the fuel feeding magazine. A lid or cover 22 is placed over the top, the lid being retained in proper position by means of an annular flange 23. The top is further provided with a flanged opening 24 to which a stack 25 is adapted to be connected.

In the use of the stove, fuel is introduced through the magazine 15 and the fire box and magazine are substantially filled with coal. The products of combustion pass

through the passage 11 to the stack 25. The space 18 effectively insulates the tubular magazine from the heated passage. By providing the inclined lower end of the inner shell, the heat is retained in the fire box and a relatively small passage is provided between the body portion of the stove and the inclined bottom of the inner shell which communicates with the bottom of the passage 11. The inclined bottom further serves to throw the heat outwardly to the heat absorbing and radiating element 7, and thus to the room to be heated. By throwing the heat outwardly, the fuel in the magazine is kept at a relatively low temperature and formation of gas is prevented. The elimination of "gassing" is an important feature of the invention and is due to the inclined bottom 14.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described my invention, I claim:

1. In a self-feeding stove, the combination with an outer shell and an inner shell

arranged therein and spaced therefrom, said inner shell being provided with an inclined bottom having a central opening, of a fuel magazine arranged within said inner shell and terminating substantially in alignment with the bottom of said inner shell, means for supporting said fuel magazine, a top having an outer flange to engage said outer shell and an inner flange to receive said fuel magazine, and a cover for said magazine resting on said top.

2. In a self-feeding stove, the combination with an outer shell and an inner shell arranged therein and spaced therefrom, said inner shell being provided with an inclined bottom having a central opening, of a fuel magazine arranged within said inner shell and terminating substantially in alignment with the bottom of said inner shell, said fuel magazine being provided with a circumferential flange on its exterior adjacent the bottom thereof adapted to be engaged by the inclined portion of said inner shell to support it, a top having an outer flange to engage said outer shell and an inner flange to receive the upper end of said fuel magazine, and a cover for said magazine resting on said top.

In testimony whereof, I affix my signature.

GEORGE G. SCARBOROUGH.
